APPARATUS FOR PERMANENTLY WAVING
HAIR

Joseph S. Cipolla, Brooklyn, N. Y.

Application December 27, 1948, Serial No. 67,348

11 Claims. (CL 132—42)

1

This invention relates to an apparatus for permanently waving hair on the human head. The present invention is a continuation-in-part of my copending application for "Method and means for hair waving," Serial No. 14,725, filed March 13, 1948.

It is an object of my invention to provide an apparatus of the character described which is particularly useful for home waving and through whose use a comparatively unskilled person can give either herself or someone else a permanent wave of professional appearance.

It is another object of my invention to provide an apparatus of the character described which is of an inherently simple construction and is extremely easy to use.

It is another object of my invention to provide an apparatus of the character described through whose use the hair is permanently waved in ringlet form, whereby not only is the first setting operation eliminated, but the basic wave is of the proper shape and character for subsequent setting operations, this being in contrast to the spiral and croquignole waves heretofore imparted which had to be reset after completion of waving.

It is another object of my invention to provide an apparatus of the character described through whose use the hair tresses are kept wound until a later stage of operations than ever reached before in permanent waving, whereby the permanency of the wave is enhanced.

It is another object of my invention to provide an apparatus of the character described which is specially adapted to be employed in conjunction with "cold wave" processes.

It is another object of my invention to provide an apparatus of the character described in which curls can be wound in any desired direction, i. e. clockwise or counterclockwise.

It is an additional object of my invention to provide an apparatus of the character described through whose use curls may be wound with ease right up to the scalp.

Other objects of my invention will in part be obvious and in part will be pointed out herein-after.

My invention accordingly consists in the features of construction, combinations of elements and arrangements of parts which will be exemplified in the constructions hereinafter described and illustrated, and of which the scope of application will be indicated in the appended claims.

In the accompanying drawings in which is

2

shown one of the various possible embodiments of my invention:

Fig. 1 is a perspective view of a waving unit embodying my invention;

Fig. 2 is an enlarged sectional view taken substantially along the line 2—2 of Fig. 1;

Fig. 3 is a sectional view taken substantially along the line 3—3 of Fig. 2;

Figs. 4 through 7 are perspective views of said unit at successive stages of a waving operation; and

Fig. 8 is a bottom view of said unit at the completion of a waving operation.

Referring now in detail to the drawings, the reference numeral 110 denotes a waving unit embodying my invention. Said unit comprises a quill 112 of a relatively rigid material, for example, a stiff plastic which is inert to the chemicals used in the hair waving process. The unit also includes a disc 114 of a flexible resilient material, i. e. an elastomer, as for example, rubber or any one of the well known elastomeric plastics, e. g. a polyethylene plastic. The quill may be solid, as indicated, and to better grip the starting end of a tress, its surface can be corrugated or fluted at least in part, as by the provision of longitudinal grooves 116 running from adjacent the rounded head 118 of the quill to a point about one-half inch from the disc. For a reason which later will be apparent, the quill flares slightly from the upper end of the un-grooved portion toward the head 118. The base end of the quill is formed with an annular groove 122 set in slightly from said end.

The disc 114 has a central aperture 124, in which the grooved portion of the quill is snugly fitted, thereby frictionally detaining the quill against rotation relative to the disc and yet enabling the quill to be turned by hand with comparative ease. The disc also includes a radial slot 126 having a constricted entrance neck. If desired, the disc may be furnished with a plurality of through openings 128 to lighten the same and make manufacture more economical. Moreover, these openings aid in circulating air for drying and expediting application of body heat to wound tresses.

Each unit 110 further includes an accessory element 130 for holding a ringlet curl against the disc 114 and for securing the disc to the root of a tress. Said accessory element consists of an elongated slender strip of material, as for example string or cord, which for expedience of manipulation may be in the form of an endless loop. Moreover, said accessory element prefer-

ably is elastic, constituting for instance a rubber band which can be stretched easily and without danger of breaking to more than twice the diameter of the disc.

The disc 114 is specially constructed for cooperation with the rubber band 130 and to this end is provided with two pairs of slits 132, 134 and 136, 138. The slits in each pair are quite close to one another (a satisfactory spacing is $\frac{1}{4}$ "') and the pairs of slits are located on opposite sides of the center of the disc, about 90° away from the slot 126. Access to the slits is facilitated by providing the same with outwardly flaring mouths. In addition, the bases of the slits are in the form of small through holes in the disc, said holes having a diameter somewhat smaller than the thickness of the rubber band. I have secured excellent results where the rubber band had an approximately square transverse section whose longest side was twice the diameter of the holes at the bottoms of the slits. The purpose of these correlated dimensions will become apparent as the description proceeds.

Optionally, the portion of the disc between the ears of each pair of slits can be extended beyond the radius of the remainder of the disc to form ears 140 which expedite handling of the disc.

The waving unit 110 is employed as follows:

The hair on a head 142 is blocked off as indicated in Fig. 4 into suitable tresses having a desired base configuration. As illustrated herein, the base configuration of the tress is approximately square. However, they may be somewhat elongated and even considerably elongated. Nevertheless, in the preferred form of my invention, wherein the hair is permanently waved in the form of ringlets, I have found that the most satisfactory results are obtained where the bases of the tresses are not considerably elongated as they are, for example, in croquignole waving. Each tress is wetted with a conventional so-called "cold-wave" softening lotion which is combed through the tress to insure even distribution. Many such solutions are well known to the art. Mention is made here, only by way of example, of a typical softening solution, to wit, one principally including a reducing agent such as ammonium thioglycollate. An end paper constituting a thin or flimsy small paper sheet is folded in half, placed around the tress and slid to the distal end of the tress so as to bind any loose hairs and uneven ends.

The disc 114 is held in an operator's habitually used hand with the quill 112 horizontally disposed, and the paper covered end of the tress is placed on the quill near the head 118 thereof. Next, the waving unit is rolled toward the scalp (Fig. 4) by turning the disc with one hand and the head of the quill with the other. This will wind the tress about the corrugated portion of the quill. The quill is shifted axially during winding, so that contiguous turns of the spirally wound tress overlap one another slightly as best illustrated in Fig. 5. When the tress has been wound to within a short distance from the scalp, for example, about one inch, and the slot 126 in the disc is registered with the tress, said tress is slid into the slot up to the enlarged base thereof. Now the unit is turned to bring the quill to a position perpendicular to the scalp as illustrated in Fig. 5, and if the tress is not wound close enough to the scalp, the quill is turned relative to the disc to draw the unit toward the head.

During the tress-winding step, the rubber band 130 was attached to the disc, said band passing

through the pair of slots 132, 134 and having a portion thereof straddling the upper surface of one of the ears 140 as shown in Fig. 4, so that the major portion of the rubber band extends from the lower surface of the disc. After completion of winding, the rubber band is stretched across the lower surface of the disc and pulled to the side of the tress facing to the mouth of the slot 126 (see Fig. 8). Then the two strands of the rubber band are slipped into the other pairs of slits 136, 138, and the rubber band is pulled taut. This action reduces the thickness of the section of the rubber band and, together with the pull on the band, permits the two strands thereof to slide easily through the slits 136, 138. Thereafter, when the manually applied tension is released, the free end of the band resumes its normal thickness and the portion of the band in the slits 136, 138 will become jammed, thereby holding in tension those parts of the band which are on the lower surface of the disc. Said tensed portions of the band engage the tress adjacent its base and press it against the disc so as to hold the disc in place against the scalp and prevent the tress from slipping. These portions of the rubber band also function to press the sides of the slot 126 against the tress. Should the foregoing manipulation of the band disturb the spacing between the disc and the scalp, or for any other reason, the quill subsequently may be turned further to bring the disc closer to the scalp.

At this time, the free or untensed portion of the rubber band extends from the upper surface of the disc (see Fig. 5). Later on, this free portion is employed for securing the tress in the shape of a pin curl. However, during the initial stages of hair treatment, said free portion remains idle.

When all the tresses have been wound, the same may be rewetted with the softening lotion. Now a towel, cloth or the like is wrapped about the head to hold in the body heat and the softening solution is allowed to work for a requisite period of time, dependent upon the strength of the lotion and the characteristics of the individual's hair. The towel then is removed and the wound tresses wetted with a conventional neutralizing lotion. Also, if desired and before the neutralizing lotion is applied, the tresses may be rinsed with clean, lukewarm water as by spraying or pouring over the wound tresses on the quills. After the neutralizing lotion has been on the hair a suitable time, depending on its strength (say 15 minutes) the quills are turned in an unwinding direction for about two complete revolutions to slightly loosen the wound tresses and then neutralizing solution is applied a second time, thus permitting the solution to penetrate to the inside of the tresses. The quills then are turned to retighten the tresses and neutralizing lotion is left to work again; this time preferably for a shorter period (say 10 minutes).

The next step is to loosen each wound tress by turning the quill in an unwinding direction for about four revolutions. Then, the tress is pushed down the quill toward the disc, such action being facilitated by the flaring contour of the quill, and the wound tress is allowed to open up enough to approximately cover the area of the disc. The flattened, curled tress is pressed against the disc manually (Fig. 6), while the quill is pulled out of the central aperture 124 and the free portion of the rubber band is pulled taut over the curl and has its two strands inserted

in the slits 132, 134. Tensed portions of the rubber band on the upper surface of the disc thus lie across the flat curled tress and hold the same in flat condition as shown in Fig. 7. When all the tresses are thus treated, they are saturated with additional neutralizing lotion.

I have found that the setting solution is not instantaneous in its action and therefore if, after such a solution is applied to the wound tress, said tress is flattened against the disc in the manner just set forth and the flattened tress left in this condition for a period of time, say 15 minutes to $\frac{1}{2}$ an hour, or even longer, while the tress dries, the tress will be permanently waved either in ringlet form or in a form approaching ringlet form. The longer the tress is left in the condition indicated in Fig. 7 the closer the permanently waved tress will assume a ringlet form. Moreover, by permitting the tress to dry in a ringlet form it will be set in such form thereby eliminating the step of setting the hair in ringlets subsequent to permanent waving.

Although it is proposed to sell all of the component elements of the hair waving unit as a combination, it is to be understood that individual component elements can be sold as replacement parts for use with other component elements of the unit.

It thus will be seen that I have provided an apparatus which achieves the several objects of my invention and meets the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described my invention I claim as new and desire to secure by Letters Patent:

1. A waving unit comprising in combination an elongated stiff quill consisting of a slender single-piece shaft and a thin flexible resilient disc, said disc having a through opening, an end of said quill being frictionally received in said opening so as to be rotatable with respect to the disc about the longitudinal axis of the quill against the frictional restraint of the walls of the opening against the quill, said disc having a through slit to receive a tress of hair wound helically along the length of the quill from the distal to the proximal end of the tress and from the free end of the quill to the end of the quill at the disc the diameter of said quill, in the zone over which hair is wound, at no point exceeding a quill diameter in said zone remoter from the disc, and the diameter of the quill at any point in said zone being at least as great as any diameter of the quill between said zone and the extreme end of the quill which is held in the disc, whereby, after hair is wound on said quill and the wound tress pushed flat against the disc, the quill can be withdrawn without disturbing the convolutions of the tress.

2. A waving unit comprising in combination an elongated quill, a thin disk, and an accessory element constituting an elongated slender strip of resilient material, said disk having a through opening, said quill being frictionally received in said opening so as to be rotatable with respect to the disk about the longitudinal axis of the quill against the frictional restraint of the walls of the opening against the quill, said disk having a slit to receive a tress of hair wound heli-

cally along the length of the quill from the distal to the proximal end of the tress and from the free end of the quill to the end of the quill at the disc, said disk additionally having a plurality of widely spaced peripheral means to engage spaced portions of said element and to permit the portion of said element between said engaged portions to hold a wound and flattened tress against said disk.

3. A waving unit comprising in combination an elongated thin quill, a disc, and an accessory element constituting an elongated slender strip of flexible material, said disc having a through opening, said quill being frictionally received in said opening so as to be bi-directionally rotatable with respect to the disc about the longitudinal axis of the quill against the frictional restraint of the walls of the opening against the quill, said disc having a slit to receive a tress of hair wound helically along the length of the quill from the distal to the proximal end of the tress and from the free end of the quill to the end of the quill at the disc, the diameter of said quill, in the zone over which hair is wound, at no point exceeding a quill diameter in said zone remoter from the disc, and the diameter of the quill at any point in said zone being at least as great as any diameter of the quill between said zone and the extreme end of the quill which is held in the disc, whereby, after hair is wound on said quill and the wound tress pushed flat against the disc, the quill can be withdrawn without disturbing the convolutions of the tress, said disc additionally having a plurality of widely spaced peripheral openings to receive said strip and permit portions of said strip to hold a wound and flattened tress against said disc.

4. A waving unit comprising in combination an elongated stiff quill consisting of a slender single-piece shaft, a thin flexible resilient disc, and an accessory element constituting an elongated slender strip of flexible material, said disc having a through opening, an end of said quill being frictionally received in said opening so as to be rotatable with respect to the disc about the longitudinal axis of the quill against the frictional restraint of the walls of the opening against the quill, said disc having a slit to receive a tress of hair wound helically along the length of the quill from the distal to the proximal end of the tress and from the free end of the quill to the end of the quill at the disc, the diameter of said quill, in the zone over which hair is wound, at no point exceeding a quill diameter in said zone remoter from the disc, and the diameter of the quill at any point in said zone being at least as great as any diameter of the quill between said zone and the extreme end of the quill which is held in the disc, whereby, after hair is wound on said quill and the wound tress pushed flat against the disc, the quill can be withdrawn without disturbing the convolutions of the tress, said disc additionally having a plurality of widely spaced peripheral openings to receive said element and permit portions of said element to hold a wound and flattened tress against said disc.

5. A waving unit as set forth in claim 4, wherein the accessory element is an endless rubber band.

6. A waving unit as set forth in claim 4, wherein the accessory element is an endless rubber band and wherein there are four peripheral openings in the disc to receive said rubber band, said openings being arranged in pairs on diametrically opposite sides of the disc.

7. A waving unit as set forth in claim 4 wherein the accessory element is a rubber band and wherein the peripheral openings in the disc have cross sectional areas less than that of the rubber band.

8. A waving unit as set forth in claim 4 wherein the quill flares toward its free end.

9. A thin flexible resilient disc for use in permanently waving hair on the human head, said disc having a through circular aperture and a through slit which extends from adjacent said aperture to the periphery of the disc, said disc additionally having a plurality of widely spaced slits in its periphery to receive an elongated slender flexible resilient member such as a rubber band for holding a wound and flattened tress against said disc.

10. A thin flexible resilient disc for use in permanently waving hair on the human head, said disc having a through circular aperture and a through slit which extends from adjacent said

5 aperture to the periphery of the disc, said disc additionally having a plurality of widely spaced slits in its periphery to receive an elongated slender flexible resilient member such as a rubber band for holding a wound and flattened tress against said disc, said slits terminating in openings smaller than the cross-sectional area of the member.

11. In combination for use in permanently waving hair on the human head a flexible resilient endless loop such as a rubber band and a thin flexible resilient disc, said disc having a through circular aperture and a through slit which extends from adjacent said aperture to the periphery of the disc, said disc additionally having a plurality of widely spaced slits in its periphery to receive said loop for holding a wound and flattened tress against said disc.

JOSEPH S. CIPOLLA.
